UNITED STATES PATENT OFFICE.

WILLIAM E. DUNSTAN, OF MODESTO, CALIFORNIA.

VALVE-LIFTER.

1,398,456.

Specification of Letters Patent. Patented Nov. 29, 1921.

Application filed November 10, 1920. Serial No. 423,114.

To all whom it may concern:

Be it known that WILLIAM E. DUNSTAN, a citizen of the United States, residing at Modesto, in the county of Stanislaus and State of California, has invented certain new and useful Improvements in Valve-Lifters, of which the following is a specification, reference being had to the accompanying drawings.

10 This invention relates to valve lifters and more particularly to valve lifters for internal combustion engines.

An object of the invention is to provide a device of this character which will readily compress the spring of the valve to permit the valve to be reached for repairs and other purposes.

Another object is to provide a valve lifter including means adapted to engage the 20 spring of the valve and a bar carried by the first mentioned means for engagement with the head of the valve, and means for moving the first mentioned means step by step longitudinally of the bar.

25 Another object is to provide a valve lifter of this character including a spring engaging arm and a bar slidably mounted on said arm, and means for actuating said bar comprising a plurality of pawls, one of said 30 pawls serving to lock the bar after each movement thereof, another of said pawls being used to move the bar in one direction, and means whereby the locking pawl and actuating pawl permit retraction of the bar.

35 A still further object of the invention is to provide a novel operating means for a valve lifter of this character including a pivoted lever, said lever being manually operable to permit movement of the bar of the 40 lifter in one direction through the medium of the pawls, and automatically and manually operable to permit movement of the bar in the opposite direction through the medium of the pawls.

45 With the above and other objects in view, the invention consists in the improved construction and arrangement of parts to be hereinafter more particularly described, fully claimed and illustrated in the accompanying drawings, in which:—

Figure 1 is a vertical elevation of a valve lifter constructed in accordance with an embodiment of the invention, the cover of the casing of the lifter being removed to show 50 the lifting mechanism.

Fig. 2 is a front elevation of the valve lifter, the casing being shown in section.

Referring to the drawings, A designates an engine cylinder including the valve B, said valve being provided with a spring C. 60

In order to compress the spring C to permit operation of the valve B independently thereof for the purpose of repairs and the like, there is provided a novel valve lifting mechanism comprising a spring supporting 65 member 5, said member including a pair of U-shaped arms 6 disposed in spaced parallel relation to each other and connected by means of bushings 7 and bolts or rivets 8. By this means the spring supporting member 70 is rendered substantial so that pressure will not distort the same. The end portion 9 of the spring supporting member is disposed in spaced relation to the end portion 10, the extremity of the end portion 10 being provided with a socket 11 having formed 75 therein a spring seat 12, said seat being adapted to engage the lower portion of the spring C when the valve is being lifted.

Carried by the end 9 of the spring supporting member is a casing 13, said casing having an opening 14 in its end 15, and an opening 16 in its end 17, the openings 14 and 16 registering. A handle 16^a projects from the end 15 of the casing, the purpose 80 of which will be hereinafter described. Slidably mounted in the casing 13, is a rack bar or plunger 18, one longitudinal edge of the bar being provided with a series of rack teeth 19. Each end of the bar is provided 85 with a stop 20 adapted to prevent disengagement of the bar from the casing. The bar 18 is intended to move toward the spring socket 11 in order to engage the head of the valve B when the valve is to be lifted. 90

To permit this operation, a novel actuating mechanism is provided, said mechanism comprising a lever 21, said lever being pivoted at its intermediate portion within the casing by means of the screw 22. The end 23 100 of the lever extends through a slot 24 formed in the side of the casing remote from the bar 18, said end having an operating handle 25 secured thereto. The end 26 of the lever is disposed within the casing and is tapered. 105 An actuating pawl 27 is pivoted to the tapered end 26, said pawl having a pin 28 extending from the lower side portion thereof adjacent the end of the pawl. A spring 29 is secured by means of the pin 30 to the 110

end portion 26 of the lever between the pivotal connection of the pawl to the lever and the screw 22, said spring being coiled about the pin 30 and then extended downwardly into engagement with the pin 28. By this means the pawl 27 is constantly urged toward the bar 18. The end 26 of the lever is normally urged upwardly within the casing by means of a spring 31, one end 10 of said spring being secured as at 32 to the side of the casing beneath the lever 21, by means of which the lever 21 is moved upwardly so as to permit the pawl 27 to engage the rack teeth 19.

15 A locking pawl 33 is pivoted in the casing 13 beneath the end 26 of the lever 21 by means of a pin 34, said pin including a recess 35 adapted to receive one end of a spring 36, said spring being coiled about 20 the pin 34 and extended downwardly into engagement with a pin 37 which projects from the end of the locking pawl 33 in angular relation thereto. This locking pawl is intended to lock the bar 18 upon completion 25 of each movement thereof toward or away from the end portion 10 of the spring support so that accidental retraction is impossible. The pawl is of course moved in a step by step fashion through the medium of the 30 actuating pawl 27 upon movement of the handle 25, the pawls 27 and 33 alternating to engage the rack teeth 19.

To permit retraction of the pawl 18 after the spring C has been compressed, without 35 causing damage to the lifter, there is provided a lever 38, said lever including an angular extension 39 on one end thereof, and having its end 40 recessed as at 41. The lever 39 is pivoted within the casing by 40 means of a pivot pin 42. By this means the body portion of the lever is disposed substantially parallel to the bar 18 and side of the casing while the extension 39 is disposed substantially parallel to the end 15 of the 45 casing. An opening 42 is provided in the end 15 of the casing, beneath which the end of the extension 39 is disposed, said extension having a recess 43. In order to prevent contact of the lever 38 with the pawls 27 and 33, when the bar 18 is being moved toward the end portion 10 of the valve support, there is provided a cam lever 44, which 50 is pivoted in the opening 42, the cam extension 45 thereof being adapted to engage the extension 39, said extension 45 being disposed in the recess 43 to prevent accidental disengagement thereof.

60 It is of course obvious, in view of the locking pawl 33 that it is impossible for the bar 18 to retract or move in the opposite direction of its own accord. To permit this however, a spring 46 is disposed within the casing 13, the end 47 of the spring being secured to the casing, while the end portion 55 48 is extended back upon the spring and dis-

posed in engagement with the end portion 40 of the lever 38 to urge the lever toward and into engagement with the pins 28 and 37 when the lever 44 is disengaged from the extension.

70 In the operation of the device, the lower portion of the spring C is disposed in the socket 11 in engagement with the spring seat 12, while the bar 18 is extended through the opening or port above the valve head 75 into engagement with the same, this operation being possible by forcing the bar 18 through the casing independently of the actuating means therein. After the device is thus positioned, the operator with one hand, 80 grasps the handle 16, operates the handle 25 and the cam lever 44 to permit contact of the lever 38 with the pawls 27 and 33. This leaves the other hand of the operator free to manipulate the keeper on the end of the 85 valve stem. The casing 13 and the spring supporting member are thereby moved upwardly on the bar in a step by step manner until the spring C has been compressed to the extent desired, whereupon the means securing the spring C to the valve stem may be unfastened to permit manipulation of the valve.

90 When it is desired to remove the valve lifter or return the spring to its normal position, the operator swings the cam lever 44 toward the rack bar 18 so as to permit the spring 46 to force the lever 38 toward the pawls 33 and 27, the end 40 of the lever 38 engaging the pin 37 and forcing the locking 95 pawl away from the teeth of the rack bar 18. During this operation the pin 28 of the pawl 27 is disposed in the recess 41 of the lever 48. After the pin 28 is moved from the recess 41, the pressure of the pawl in 100 engagement with the rack bar forces the lever 38 away from the pawl 33 against the tension of the spring 46 whereupon the spring 36 forces the locking pawl 33 into engagement with the rack bar 18 to thereby 105 permit movement of the casing 13 and the spring supporting arm in a step by step fashion on the bar 18, the speed of this movement being controlled by the operator through the medium of the handle 25. This 110 operation is continued to alternately engage and disengage the pawls 33 and 27 from the rack bar 18 until the spring C expands to its normal position. When the lower end of the 115 rack bar is moved to a point in alignment with the end portion 9 of the spring support 120 5, the device may be readily disengaged from the engine.

125 From the foregoing it will be readily seen that this invention provides a novel form of valve lifter capable of being readily applied to the engine and operated to efficiently compress the spring of the valve regardless of the strength of the spring and wherein it is impossible for the casing and 130

supporting arm to move accidentally longitudinally of the rack bar through the medium of the spring C of the valve, and as a double locking action is afforded by the 5 pawls 27 and 33 danger of the device accidentally slipping and releasing the spring is eliminated.

What is claimed is:—

1. A device of the character described comprising a body member, a rod slidable in said body member, means engaged with the rod for moving said body member in one direction on the rod, means engaged with the rod for preventing accidental movement of the 10 rod in the same direction through the body member and means for disengaging the first mentioned and second mentioned means from the rod to permit movement of the body member in either direction on the rod.
2. A device of the character described comprising a body member, a rod slidable in said body member, means for moving said body member in one direction on the rod, means preventing accidental movement 15 of the rod in the opposite direction, and means coacting alternately with the first and second mentioned means to permit gradual movement of the body member in the last mentioned direction upon actuation of the first mentioned means.
3. A device of the character described comprising a body member, a rod slidable in said body member, means for moving said body member in one direction on the rod, 20 means preventing accidental movement of the rod in the opposite direction, means coacting alternately with the first and second mentioned means to permit gradual movement of the body member in the last mentioned direction upon actuation of the first mentioned means, and means carried by the 25 body member for rendering the third mentioned means inoperative when the body member is moved in the first mentioned direction.
4. A device of the character described comprising a casing, a supporting arm carried by the casing, a bar movable through the casing toward and away from the arm, 30 manually operative means carried by the casing for moving the casing and arm in one direction on the bar, automatically operable means carried by the casing to prevent movement of the bar in the opposite 35 direction, and means carried by the casing and coacting with the first and second mentioned means to prevent movement of the 40

casing, and arm in the last mentioned direction.

5. A valve lifter comprising a casing having a supporting arm, a rack bar slidable through said casing, an actuating pawl mounted in the casing, and adapted to engage the rack bar, a locking pawl mounted in the casing and adapted to engage the rack 60 bar, a lever mounted in the casing and means carried by the casing and yieldably urging the lever toward the actuating and locking pawls, to cause alternate disengagement of said pawls from the rack bar through the 65 medium of the actuating pawl.

6. A valve lifter comprising a casing having a supporting arm, a rack bar slidable through said casing, an actuating pawl mounted in the casing, and adapted to engage the rack bar, a locking pawl mounted in the casing and adapted to engage the 70 rack bar, a lever mounted in the casing and means carried by the casing for yieldably urging the lever toward the actuating and locking pawls to cause disengagement of the locking pawl from the rack bar when the actuating pawl is engaged with the rack bar.

7. A valve lifter comprising a casing having a supporting arm projecting therefrom and adapted to embrace a spring pressed valve stem and support the spring of the valve, a rack bar slidable through said casing, a manually operable actuating pawl 90 mounted in the casing and adapted to engage the rack bar, an automatically operable locking pawl mounted in the casing and adapted to alternately engage the rack bar with respect to the actuating pawl, a lever 95 mounted in the casing, one end of said lever having a recess, the other end of said lever being disposed in angular relation to the body portion thereof, means carried by the casing and adapted to engage the last mentioned end of the lever to move the lever away from the pawls, the first mentioned end portion of the lever being adapted to engage the locking pawl to disengage said pawl from the rack bar, the recessed portion 100 of the lever extending over a portion of the actuating pawl to prevent disengagement of the pawl from the rack bar, said actuating pawl causing disengagement of the lever from the locking pawl when the actuating 105 pawl is moved from the recess.

In testimony whereof I hereunto affix my signature.

WILLIAM E. DUNSTAN.
